GRINDING WHEEL AND MOUNTING
THEREFOR

Charles J. Phillips, Kaukauna, Wis.

Application September 30, 1940, Serial No. 359,068

1 Claim. (Cl. 51—168)

Heretofore grinding wheels of this character have been provided with an arbor or shaft opening therethrough and the wheel has usually been secured to the shaft through the medium of clamping discs mounted upon the shaft and between which discs the wheel is located. The other faces of the disc contact the adjacent flat surfaces or faces of the grinding wheel, with the result that the wheel is secured to the shaft for rotation therewith, by friction.

It frequently happens that the wheel becomes cracked or broken, and by reason of the high speed of rotation of the wheel, portions or segments thereof will become dislodged from their frictional gripping means and will be thrown out by centrifugal force, often resulting in serious damage.

To overcome these difficulties and objections and to provide improved means for preventing portions of the wheel from being thrown out by centrifugal force, in the event the wheel becomes broken, is one of the objects of the present invention.

A further object is to provide improved means for strengthening and reinforcing the wheel.

To the attainment of these ends and the accomplishment of other new and useful objects as will appear, the invention consists in the features of novelty in substantially the construction, combination and arrangement of the several parts hereinafter more fully described and claimed and shown in the accompanying drawing, illustrating this invention, and in which

Figure 1 is a front elevation of a grinding wheel of this character constructed in accordance with the principles of this invention.

Figure 2 is a sectional view showing a grinding wheel of this character secured to the end of an arbor or shaft.

The grinding wheel 10 is constructed of any suitable abrasive material, such as emery or the like, and may be of any desired thickness and diameter, there being an opening 11 therethrough at the diametric center thereof and through which opening the end 12 of a shaft or arbor 13 passes.

Formed integral with the wheel 10 is a projecting rib 14 which is preferably arranged concentric to the periphery of the wheel 10 and is spaced a substantial distance therefrom. The rib 14 is also arranged concentric to the axis of the disc and is preferably spaced for a substantial distance therefrom. One of these ribs 14 is arranged on both sides of the wheel 10 and are preferably in alignment with each other.

The ribs 14 are preferably of a substantial diameter in cross-section and are formed preferably from the same material as that from which the wheel 10 is constructed.

5 The numeral 15 designates clamping members preferably in the form of discs of diameters considerably less than the diameter of the wheel 10. In one face of each of these discs 15 is arranged an open annular groove 16. These grooves are spaced a substantial distance from the periphery of the discs 15.

In assembling the parts and to secure the wheel 10 to the end 12 of the shaft 13, one of the discs is placed upon the end 12 so that its face 15 will contact a shoulder 18 on the shaft 13. The wheel 10 is then placed upon the end 12 so that one of the ribs 14 will enter the groove or recess 16 and the face 19 of the disc will contact the adjacent face of the wheel.

15 The other disc 15 is then placed in position so that the groove or recess 16 therein will receive the rib 14 while the face 20 of the disc will contact the adjacent face of the wheel 10. A washer 21 may then be sleeved upon the shaft to contact the outer face of the outermost disc and a nut or collar 22 may be threaded upon the screw threaded end 23 of the shaft to engage the washer and to co-operate with the shoulder 18 for clamping the parts firmly together.

20 With this improved construction it will be manifest that the wheel 10 will be secured to the shaft or arbor by friction and which friction is sufficient under normal conditions to cause the wheel 10 to turn with the shaft.

25 Should it so happen that the wheel 10 of this construction should become broken, it will be manifest that none of the broken parts can be thrown outwardly by centrifugal force by reason of the fact that the ribs 14 engaging and being seated in the grooves or recesses 16, and which ribs extend entirely around the face of the wheel, will hold the broken parts in assembled relation.

30 Furthermore, the ribs 14 serve as a means for reinforcing or strengthening the wheel. Obviously any other means may be provided for fastening the disc 15 to the shaft.

35 While the preferred form of the invention has been herein shown and described, it is to be understood that various changes may be made in the details of construction and in the combination and arrangement of the several parts, within the scope of the claim, without departing from the spirit of this invention.

40 45 50 55 55 What is claimed as new is:

A grinding wheel provided with annular ribs projecting from the lateral faces thereof, disposed between the periphery and the axis of the wheel and spaced from both, the remaining portion of the lateral faces of said wheel being flat, the thickness of the wheel on both sides of said ribs being substantially uniform through the area thereof, an arbor upon which the wheel is mounted, spaced rigid discs mounted upon the arbor and between which discs the wheel is disposed, 10

there being an annular groove in the faces of the respective discs which are adjacent the wheel for receiving said ribs, the remaining portions of said faces of the discs being flat, and means 5 for clamping the flat surfaces of the discs in contact with the flat faces of said wheel, whereby the entire inner faces of the discs will be held in contact with the proximate faces of the wheel.

CHARLES J. PHILLIPS.
